UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 18, 1921. Serial No. 425,821.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening hoods or casings for typewriting machines of the same general type shown in my application, Serial No. 466,820, filed May 4, 1921, and in the application of B. C. Stickney, Serial No. 429,617, filed December 10, 1920.

15 The invention comprises a hood having a body part and a cover part hinged to said body part, said body part having an opening in the front thereof large enough to permit a typewriting machine to be inserted into 20 the casing, a front plate being mounted on the body part to close the front opening.

It is one feature of this invention to provide a hood or casing which shall effectively 25 deaden sounds produced by the machine during the typing operation. For this purpose, the body part and the cover part each comprise parallel, spaced walls, so that sounds striking the inner wall must pass an air space before reaching the outer wall, said 30 air space acting as a cushioning means to deaden the vibrations. The body part and the cover part are each preferably separate closed units, and each of said units may be constructed of two substantially similar 35 members, one slightly larger than the other, so that one fits within the other and is separated therefrom by an air space. Thus, the body part comprises substantially two similar members, each of which has substantially 40 the shape of the complete body part, but one of which is smaller than the other to enable it to fit therein. Similarly, the cover part comprises substantially two similar members of slightly different sizes fitted one 45 within the other and separated by an air space. The similar members of both the body part and the cover part may be assembled by sliding one member vertically 50 into the other.

55 The walls of the body part and the cover part are provided with corrugations or indentations which strengthen the surface of the casing, fastening means passing through the indentations of the walls to grip the inner and outer walls without unduly dis-

torting them. Each fastening means forms a connecting link between the inner and the outer walls, and would ordinarily carry sounds from the interior to the exterior. To prevent such transmission of sounds, pads or washers of sound-deadening material are interposed between the walls, each of said fastening means passing through the walls and through a pad of sound-deadening material. The pads are positioned in recesses in the inner members and are thus held in position while the members of each part are assembled by sliding one member into the other.

The inner and the outer members of both 70 the cover part and the body part may be constructed preferably by overlapping plates riveted together, the inner and outer members of each part being connected at their outer ends to form closed containers. For 75 this purpose, the inner members and the outer members may each be provided at their upper or lower ends with flanges which overlap the edges of the other member to close the upper or lower openings between 80 the walls. To close the openings at the front side edges, where the inner and outer members terminate, there may be provided an additional flange on one of the members 85 adjacent one side edge and overlapping the side edge of the other member.

When the sound-deadening casing is applied to the machine, it is found that the front wall of the body part extends upwardly to a point in proximity to the margin-stops on an ordinary Underwood standard typewriting machine. To allow easier access to the margin-stops, platen-rotating means and other mechanism associated with the typewriter carriage, the upper portion 90 of the front plate of the body part is hinged so that it may be swung to lowered position, thus providing a larger space at the front of the machine in the vicinity of the carriage. Means are provided whereby the 100 raising of the cover will cause the simultaneous lowering of the hinged portion of the front plate. To aid the cover in its upward movement, there is provided a linkage 105 between the body part and the cover. It is a feature of this invention to connect the means for lowering the hinged portion of the cover with the cover-opening linkage, so that, when the cover is raised, the hinged portion of the front plate will be swung to 110

lowered or ineffective position. The hinged portion at the front of the body part is normally pressed upwardly and rearwardly to raised or effective position by means of 5 springs, said springs restoring the hinged part to its normal position when the cover is lowered and the means which operated to swing the hinged portion downwardly to lowered position is withdrawn.

10 In another form of the invention, there may be used, instead of the pads as spacers between the walls of the body part and the cover, sheets of sound-deadening material, such as felt, cardboard or any other suitable 15 sound-deadening material, extending between said walls, thus forming three plies and double air chambers in all of the walls.

Other features and advantages will hereinafter appear.

20 In the accompanying drawings,

Figure 1 is a perspective view of an Underwood standard typewriting machine with the sound-deadening casing or hood applied thereto.

25 Figure 2 is a view similar to Figure 1, but showing the cover of the casing in raised position.

Figure 3 is a side view, vertically sectioned, of the device shown in Figure 1 and 30 showing the structure of the walls of the casing.

Figure 4 is a front view, partly sectioned vertically, of the body part and cover part, said parts being disassembled.

35 Figure 5 is a plan view of the device as shown in Figure 1, partly in section, the cover part having been removed.

Figure 6 is a sectional side view of the 40 cover, showing the arrangement of the three-ply walls.

Figure 7 is a sectional plan view of one end of the body part of the form of the invention illustrated in Figure 6.

The Underwood standard typewriting 45 machine comprises a main frame 10, which may be supported upon a base 11 by supporting feet 12, said frame having a forward extension 13, in which are positioned banks of keys 14 to operate type-bars, not shown, and cause types carried by said type-bars to print against a platen 15, journaled in the end walls 16 of a platen-frame 17. Said platen-frame forms part of a carriage 19 mounted for letter-feeding movement upon 50 a front rail 20 and a rear rail 21 fixed to the main frame. The carriage comprises various forwardly and downwardly-extending operating members, such as the carriage-release lever 22, the carriage-return finger-piece 23, and the line-space handle 24, said carriage-release lever being guided in its movements by a bracket 25 fixed to the carriage-return finger-piece 23.

55 For deadening the sounds arising in the typing operation, there is provided a hood

or casing having a body part 30 and a cover part or cover 31 hinged at 32 to said body part. The body part comprises a rear wall 35, side walls 36, and a front wall in the form of two end portions 37, said portions being spaced laterally to provide an opening through which the machine may be inserted into the casing, said machine being positioned within said casing by abutments 40 fixed to the rear wall 35 and contacting with the rear posts of the main frame 10. When the machine is so positioned within the casing, the forward extension 13 projects forwardly from the front wall of the casing. For closing all of said front opening not occupied by the forward extension, there is provided a front plate 41 which is mounted upon the portions 37 by means of hooks 42 projecting between said portions and engaging pins or studs 43 fixed to the portions 37, 55 said hooks being fixed to front slides 39 mounted upon the front plate 41 by means of studs 44 which guide said slides in their upward movement, said slides having finger-pieces 45, whereby they may be raised to release hooks 42 from pins 43, or lowered to cause said hooks to engage said pins.

The machine is then enclosed at the rear, sides, and front, and, to enclose the machine at the top, there is provided the cover 31 having a rear wall 50, a top wall 51 provided with a transparent plate 52 to permit the interior of the casing to be viewed, said rear and top walls forming a ceiling for the cover part, a front wall 53 terminating above the front plate 41, and side walls 58. A space or slot is thus provided between the lower edge of wall 53 and the upper edge of plate 41, through which the various carriage-operating levers extends. To close all of the slot not actually occupied by these levers, there is provided a set of co-operating cushions 54 and 55, each of said cushions comprising folds or loops of sound-deadening material, such as plush, felt, or soft leather, the two-ply margins of said loops being clamped between bars 56 to form a unit, one of which is mounted on the front wall 53, so that cushion 54 extends downwardly, and the other of which is mounted on front plate 41, so that cushion 55 extends upwardly, said cushions contacting to close the slot. The cover may be raised by means of a finger-piece 57 and swung about hinge 32 to permit access to the machine. To aid in raising the cover, there may be provided a linkage comprising a bell-crank 60 pivotally mounted on the side wall of the body part, one arm 61 of said bell-crank being connected to one end of a link 62 pivotally mounted on the cover at 63. To another arm 65 of said bell-crank is attached one end of a spring 66, the other end of which is connected to a bracket 64 fixed on the side wall of the casing. The spring normally 100

tends to rotate the bell-crank, so that arm 65 moves forwardly and arm 61 upwardly and rearwardly to force link 62 rearwardly and thus raise the cover. The weight of the cover normally withstands the force of the spring which tends to open it, but, when the cover is raised by hand, the spring relieves the operator of the necessity of using a large amount of force. The opening movement of the cover is limited by a third arm 68 contacting with the pin 69 fixed to the side of the body part. It will be understood that the cover-opening linkage may be duplicated at the other side of the casing.

It will be seen that the front plate 41, with its attached cushion 55, extends upwardly to about the middle of the platen or on a line with the margin-stops 70. To permit greater access to these margin-stops and to the platen-rotating knobs 71, as well as to other mechanism associated with the carriage, it is desirable that the front plate terminate some distance below the margin-stops. To maintain the slot in closed position, and still provide the necessary space to allow access to the carriage mechanism, the front plate is provided with a hinged portion 72, which may be swung about a hinge 73, but which is normally pressed upwardly into slot-closing position by springs 74 (Figure 1).

It is desirable that the hinged portion 72 shall be lowered simultaneously with the opening of the cover and without an additional operation. For this purpose, there is provided a link 75 guided for movement on the side of the body part by a headed stud 76 operating in a slot 77 in said link, said link being connected to the branch or arm 65 of the bell-crank. As previously described, upon opening the cover, the arm 65 moves forwardly, and, hence, link 75 will move forwardly, so that the forward end of said link, which contacts with an abutment or extension 78 on the hinged portion, will press forwardly against said abutment to swing the hinged portion forwardly and downwardly to lowered position (Figure 3) against the action of springs 74. It will be apparent that, when the cover is lowered, arm 65 and link 75 will move rearwardly, and the forward end of link 75 will be withdrawn from abutment 78 to permit springs 74 to swing the hinged portion upwardly and rearwardly to effective or slot-closing position. A link 75 may be provided at each side of the casing if a cover-opening linkage is mounted at each side.

To further deaden the sounds arising in the typing operation, both the body part and the cover part comprise double walls spaced apart, so that sounds which are transmitted by the inner wall must pass through the space between the walls before reaching the outer wall, thus effectively deadening the

sounds. For this purpose, the body part and the cover part each comprise two similar members, one smaller than the other and fitted within the other, the inner member of each part being spaced from the outer member. Thus, the body part comprises an inner member or inner body part 80 and an outer member or outer body part 81, said inner member comprising an inner rear wall 83, (Figures 3 and 5), inner side members 84, (Figures 4 and 5), and inner front portions 85, (Figure 5), said inner rear wall, side members, and front portions being preferably separate plates riveted together. Similarly, the outer body part 81 comprises an outer rear wall 86, outer side members 87, and outer front portions 88, said outer rear wall, side members, and front portions being preferably riveted together in a manner similar to the inner body part. The inner body part is provided on its upper edges with flanges 89 to overlie the corresponding upper edges of the outer body part, and the outer body part is provided on its lower edges with flanges 90, upon which rest the lower edges of the inner body part. To assemble the body part, therefore, it is only necessary to slide the inner body part downwardly into the outer body part, until the flanges 89 rest upon the upper edges of the outer body part, and the lower edges of the inner body part rest upon the flanges 90 of the outer body part. To close the openings between the inner and outer body parts at the front, along the front side edges, one of said body parts (here shown as the outer body part) may be provided with flanges 91 to overlie the side edges of the other body part. The walls of the inner and outer parts are provided with co-operating corrugations or indentations 92 to strengthen the walls, and fastening members 93 are passed through these walls to hold the walls together and are countersunk in the indentations. There are interposed between the walls to keep them spaced from each other, sound-deadening washers or pads 94, through which the fastening members may be passed. Said pads are seated in recesses 95 in the walls of the inner body part, and are provided with indented surfaces 96 for co-operating with the indentations 92 of the outer body part, so that, when the parts are assembled, the pads may be placed in the recesses of the inner body part before it is slid down into the outer part, the indented surfaces 96 of the pads sliding along the indentations 92 of the outer wall during the assembling of the body part. The corrugations or ribs 92 co-operate with the inner and outer walls to form a multiplicity of sound-deadening air-pockets.

Similarly, the cover part 31 comprises an inner member 100 and an outer member 101, said members being similar in shape, but

the inner member being somewhat smaller, so that it may fit within the outer member and be spaced therefrom. The inner member 100 comprises an inner rear and top 5 wall, or ceiling, 102 and inner side walls 103, while the outer cover part comprises an outer rear and top wall, or ceiling, 104 and outer side walls 105 (Figures 3 and 4). Both the inner and the outer cover parts 10 are cut out to provide the necessary opening for the transparent plate 52. The inner cover part is provided, at its lower rear edge, with flanges 106, so that, when the inner and outer cover parts are assembled, 15 the inner cover part need only be inserted upwardly within the outer cover part, or the outer cover part moved downwardly over the inner cover part until the bottom edges of the outer cover part rest 20 upon the flanges 106. The inner and outer cover parts are provided with indentations or corrugations 107 similar to the indentations 92 of the body part, and are similarly fastened by bolts or rivets 108 similar 25 to rivets 93 passing through the indentations in the inner and outer walls of the cover part and through pads 109 of sound-deadening material, similarly seated in recesses in the inner cover part.

30 Instead of pads 94, there may be used to space the inner and outer members 80 and 81 from each other, sheets 110 which may be composed of felt, cardboard, leather, or any other sound-deadening material, said sheets 35 extending parallel with the inner and outer members, as indicated in Figure 7. In a similar way, the inner and outer members 100 and 101 of the cover part may be spaced from each other by sheets 111. With this 40 arrangement, it will be seen that there are provided two chambers and three parallel layers in each wall of the body part and the cover part of the casing, thus adding to the sound-deadening effect of the casing.

45 Variations may be resorted to within the scope of the invention, and portions of the improvements may be used without others.

Having thus described my invention, I claim:

50 1. A sound-deadening casing for a typewriting machine having a carriage and a finger-piece projecting therefrom, said casing comprising a body-part having a front wall, a cover forming with the top of said 55 front wall a slot through which the finger-piece projects to travel therealong with the carriage, the upper part of said front wall being shiftable downwardly, and cover-controlled means for shifting said portion 60 of the front wall downwardly during the lifting of the cover to open the slot in both directions, and upwardly to effective position during the closing of the cover.

65 2. A sound-deadening casing for a typewriting machine with a cross-member at the

front and top thereof and margin-stop finger-pieces beneath said cross-member, said casing comprising a body-part with the front wall extending above said finger-pieces, and having its upper part movable 70 with respect to the rest of the wall, a cover for said body-part, and cover-controlled means for shifting the movable part of said front wall to a position to expose said finger-pieces when the cover is open and to restore 75 said upper part to effective position during the closing of the cover.

3. In combination, a typewriting machine and a sound-deadening casing fitted thereto, 80 said casing comprising a body-part and a sound-deadening cover-part, said body-part comprising walls positioned one within the other and spaced from each other, the outer walls being formed with inwardly-projecting ribs for strengthening the walls, and the inner walls being provided with outwardly-projecting ribs opposite those in the outer walls, said ribs and walls co-operating to form a multiplicity of sound-deadening air-pockets, and means for fastening the walls 90 together.

4. In combination, a typewriting machine and a sound-deadening casing fitted thereto, 95 said casing comprising a cover-part and a sound-deadening body-part, said cover-part comprising walls positioned one within the other and spaced from each other, the outer walls being formed with inwardly-projecting ribs for strengthening the walls, and the inner walls being provided with outwardly-projecting ribs opposite those in the outer walls, said ribs and walls co-operating to form a multiplicity of sound-deadening air-pockets, and means for fastening the walls 100 together.

5. A sound-deadening casing for a typewriting machine having a carriage and mechanism associated with the carriage, 110 said casing comprising a body part and a cover part hinged at the rear to said body part, said body part having a front opening through which the machine may be inserted into the casing, and a front plate for closing said front opening, said front plate having 115 an upper hinged portion which may be swung downwardly to allow greater access to said carriage and its associated mechanism.

6. A sound-deadening casing for a typewriting machine having a carriage and mechanism associated with the carriage, 120 said casing comprising a body part and a cover part hinged at the rear to said body part, said body part having a front opening through which the machine may be inserted into the casing, and a front plate for closing said front opening, said front plate extending 125 upwardly in front of said carriage, said front plate having an upper hinged portion 130

which may be swung downwardly about an axis below the carriage to allow greater access to said carriage and its associated mechanism.

5. 7. In combination, a typewriting machine and a sound-deadening casing fitted thereto, said machine having a carriage and handle-mechanism associated with the carriage, said casing comprising a body-part and a cover hinged thereto to lift up and off therefrom, said handle-mechanism projecting between said body and cover, said body-part comprising a front wall extending upwardly in front of said carriage, said front wall having at its upper edge a portion which may be moved downwardly, and inaccessible mechanism co-operating with said carriage and rendered accessible by the downward movement with said upper wall portion.

20. 8. A sound-deadening casing for a typewriting machine having a carriage and various operating levers extending forwardly from said carriage, said casing comprising a body part and a cover part hinged at the rear to said body part, said body part comprising a front wall, said front wall having an upper hinged portion which may be swung downwardly to allow greater access to said carriage and its associated mechanism, said cover part and body part forming a slot at the front through which the carriage-operating levers extend, and means for closing all of the slot not occupied by the levers, said means comprising a pair of co-operating cushions, one of said cushions being mounted on the cover part and the other of said cushions on the hinged portion of the front wall, so that said cushions contact, the cushion on the hinged portion being swingable with said portion.

45. 9. In combination, a typewriting machine and a sound-deadening casing fitted thereto, said machine having a carriage and mechanism associated with the carriage, said casing comprising a body part and a cover hinged at the rear to said body part, said body part comprising a front wall, handle-mechanism projecting from said carriage through a sealed slot between said cover and said front wall, said front wall having a hinged upper portion which may be swung downwardly to afford access to said associated mechanism, and cover-controlled means for swinging said hinged portion downwardly when the cover is raised and upwardly when the cover is lowered.

60. 10. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its

associated mechanism, means actuated by the opening of the cover part for swinging the hinged portion downwardly, said means being withdrawn when the cover part is lowered, and spring means for restoring the hinged portion to upper position when the cover part is lowered.

11. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a link mounted on said body part for forward and rearward movement and engaging said hinged portion to swing it downwardly when the link is moved forwardly, and means connecting said link to said cover part so that said link is moved forwardly when the cover part is raised.

12. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a link mounted on said body part for forward and rearward movement and engaging said hinged portion to swing it downwardly when the link is moved forwardly, means connecting said link to said cover part so that said link is moved forwardly when the cover part is raised, said link being withdrawn when the cover part is lowered, and spring means for restoring the hinged portion to upper position when the link is withdrawn.

13. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, means connected to said body part and cover part to aid in opening said cover part, and means connected to said last-named means to swing said hinged portion downwardly when the cover part is raised.

14. A sound-deadening casing for a typewriting machine having a carriage and mechanism associated with the carriage, said casing comprising a body part and a cover part hinged at the rear to said body part, said body part comprising a front wall, said

front wall having an upper hinged portion which may be swung downwardly to allow greater access to said carriage and its associated mechanism, spring means for normally pressing said hinged portion upwardly and rearwardly, means connected to said body part and cover part to aid in opening said cover part, and means connected to said last-named means to force said hinged portion downwardly and forwardly against the action of said spring means when the cover part is raised.

15. In combination, a typewriting machine and a sound-deadening casing therefor, said machine having a carriage and mechanism associated with the carriage, said casing comprising a body part having an open front, a cover hinged to said body part at its rear, and closing means for said open front, comprising a front plate attachable to said body part, and having at its upper edges a hinged portion to permit ready access to the upper front part of the machine without detaching said front plate; said carriage having a handle-device projecting through a sealed slot extending between said cover and said hinged portion.

16. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a bell-crank pivotally mounted on said body part, a link connected to said cover part and to one arm of the bell-crank to move said arm rearwardly and move a second arm of the bell-crank forwardly when said cover part is raised, and a second link connected to the second arm of the bell-crank and contacting with the hinged portion so that said second link moves forwardly to swing the hinged portion downwardly when the cover part is raised.

17. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a bell-crank pivotally mounted on said body part, a link connected to said cover part and to one arm of the bell-crank to move said arm rearwardly and move a second arm of the bell-crank forwardly when said cover part is raised, a spring fixed to said second arm and to said body part to assist in raising the cover by

drawing said second arm forwardly, and a second link connected to the second arm of the bell-crank and contacting with the hinged portion so that said second link moves forwardly to swing the hinged portion downwardly when the cover part is raised. 79

18. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a bell-crank pivotally mounted on said body part, a link connected to said cover part and to one arm of the bell-crank to move said arm rearwardly and move a second arm of the bell-crank forwardly when said cover part is raised, a second link connected to the second arm of the bell-crank and contacting with the hinged portion so that said second link moves forwardly to swing the hinged portion downwardly when the cover part is raised, and means for guiding said second link in its forward movement. 75

19. A sound-deadening casing for a typewriting machine having a carriage and mechanism associated with the carriage, said casing comprising a body part and a cover part hinged at the rear to said body part, said body part comprising a front wall, said front wall having an upper hinged portion which may be swung downwardly to allow greater access to said carriage and its associated mechanism, a bell-crank pivotally mounted on said body part, a link connected to said cover part and to one arm of the bell-crank to move said arm rearwardly and move a second arm of the bell-crank forwardly when said cover part is raised, a second link connected to the second arm of the bell-crank and contacting with the hinged portion so that said second link moves forwardly to swing the hinged portion downwardly when the cover part is raised, 90 190

20. A sound-deadening casing having a slot along which a finger-piece on the carriage travels, slot-sealing means including a yieldable lip extending along the said slot, and a lip-support pivoted to swing outwardly to open the slot. 110 115 120
